INVENTOR

Victor A. Benson

John A. Griswold

BY

ATTORNEY

UNITED STATES PATENT OFFICE.

VICTOR A. BENSON, OF SAN JOSE, CALIFORNIA.

BUILDING CONSTRUCTION.

Application filed November 1, 1921. Serial No. 512,155.

To all whom it may concern:

Be it known that I, VICTOR A. BENSON, a citizen of the United States, and resident of San Jose, in the county of Santa Clara and 5 State of California, have invented certain new and useful Improvements in Building Construction, of which the following is a specification.

My invention relates to building construction such as is used in the erecting of garages, 10 shops, etc.

It is an object of my invention to provide a building construction that is easily and quickly assembled and erected with a minimum of expense for material and labor. 15 Another object is to provide a building of the character indicated which is entirely constructed of metal thus making the same light in weight and absolutely fireproof. Still 20 another object is to provide a building constructed as indicated which may be quickly disassembled and readily packed in a small space for transportation.

In the drawing,—

25 Figure 1 is a front elevation of a building showing my improved methods of construction and assembly.

Figure 2 is an enlarged section on line 2—2 of Figure 1.

30 Figure 3 is an enlarged section on line 3—3 of Figure 1 showing the method of forming the corner lap of the metal covering.

Figure 4 is an enlarged elevation showing 35 my method of assembling the studding, rafters and the ceiling joists.

Figure 5 is an enlarged section on line 5—5 of Figure 1.

Referring more particularly to the drawings, at 1 I show the ground sill upon which 40 the building is erected. On sill 1 is a metal sill 3 composed of angle iron to which the studdings 2 are bolted by means of bolts 15. Said studdings 2 are also composed of angle 45 iron as shown and are arranged equal distances from each other in a vertical plane. and are held in this relation by means of a metal sill 3 at the bottom and by a similar metal plate 4 bolted thereto at their upper ends as shown at 15a.

50 The rafters 5 are cut as shown and are secured together by means of bolt 6 and angle iron strip 7 at the peak while the outer ends of the same are secured by means of brace plate 8 and the ceiling joists 9. By means 55 of this method of construction I assemble the rafters 5, ceiling joists 9 and the two

brace plates 8 on the ground and then raise the same into place upon the studding as a unit and secure the unit in place by means of bolts as shown in Figure 4.

60 All rafter units are of the same construction with the exception of the first unit at each end of the building. This unit having three additional vertical braces 10—11—12 together with a horizontal brace 13 all being 65 bolted together in the positions shown.

In the studdings 2 are arranged a number 70 of holes as 14 which correspond with holes in the corrugated sheet iron with which the building is covered. This sheet iron covering being shown at 18 and is bolted to the frame work by means of bolts passing through the above mentioned holes. The construction of the joints at the four corners 75 of the building is shown clearly in Figure 3.

Riveted to the two studdings 2 which come 80 on each side of the door-way is an angle iron 16 which acts as a stop for the door while at 17 is shown another angle iron bolted to the stud 2 and having the sheet 85 iron covering clamped between angle irons 2 and 17 as shown in Figure 5.

It is now apparent that I have so arranged the several parts of the building that 85 the same may be easily and quickly erected with a minimum expense of material and labor while at the same time making the structure strong but light of weight and absolutely fireproof, the same being constructed entirely of metal. The angle irons used 90 throughout the structure are L-shaped in transverse cross section. The whole structure may readily be disassembled and moved to another location with very little expense 95 and trouble. The same construction may be used in a small private garage or in a large commercial building by merely increasing the number of parts and properly arranging the struts and braces.

100 The corner construction shown in Figure 3 is particularly desirable since the natural curve of the corrugated sheet iron is utilized in part to effect a rounded corner presenting no sharp edges. This rounded corner also provides a water-tight joint since the spring 105 of the metal assists in effecting close contact of the parts.

The door construction shown in Figure 5 provides a strong, rigid and slightly jamb built entirely of metal and perfectly water 110 tight.

It is to be understood, of course, that while

I have herein shown and described one particular method of construction and assembly, that changes in form and construction and method of assembling may be made within 5 the scope of the appended claims.

I claim:-

1. A building construction comprising a framework built up of angle irons L shaped in transverse cross section and sheet 10 metal covering said framework, said framework having a door opening formed therein, each side element of said opening being formed of a pair of vertically extending and horizontally spaced angle irons each ar- 15 ranged with one flange parallel with the wall in which it is placed and the other flange arranged at right angles thereto and extending toward the interior of the structure and a third angle iron arrangd with 20 one flange inserted between the inwardly ex- tending flanges of said parallelly arranged angle irons and another flange extending laterally to form a door stop.

2. A building construction comprising a 25 framework built up of angle irons L shaped in transverse cross section, said framework having a door opening formed therein, each side element of said opening being formed of a pair of vertically extending and hori- 30 zontally spaced angle irons, each arranged with one flange parallel with the wall in which it is placed and the other flange ar- ranged at right angles thereto and extending toward the interior of the structure, and 35 a third angle iron arranged with one flange inserted between the inwardly extending flanges of said parallelly arranged angle irons and another flange extending laterally to form a door stop, and sheet metal cover- 40 ing for said framework having an edge in- serted between said parallel and spaced angle irons and rigidly secured thereto.

3. A building construction comprising a 45 framework built up of angle irons L shaped in transverse cross-section and sheet metal covering said framework, said framework having a door opening formed therein, each side element of said opening being formed

of a pair of vertically extending parallel and horizontally spaced angle irons each ar- 50 ranged with one flange parallel with the wall in which it is placed and the other flange ar- ranged at right angles thereto and extend- 55 ing toward the interior of the structure, and a third angle iron arranged with one flange inserted between the inwardly ex- tending flanges of said parallel angle irons and secured to the outermost of said angle irons, and the other flange extending later- 60 ally to form a door stop.

4. In a construction of the character in- 65 dicated, a door frame structure built up of angle irons L shaped in transverse cross- 70 section the said frame comprising a pair of spaced and parallel angle irons, means for detachably securing the two angle irons to- 75 gether, and a third angle iron having one flange inserted between two corresponding flanges of said first mentioned angle irons and riveted to the outermost of said flanges, 80 and having another flange extending later- 85 ally to form a door stop.

5. A building framework of angle irons L shaped in transverse cross-section and com- 75 prising a sill studding and plate bolted to- 80 gether, rafters notched to engage said plate, each pair of rafters being bolted together at their upper ends and spaced at their 85 lower ends by a ceiling joist bolted there- 90 to, and a brace plate bolted to the lower end of each rafter, one end of each ceiling joist and the upper end of the adjoining stud-

6. In building construction, a metal 85 framework, and corrugated sheet metal 90 covering for the same, the sheet metal on one side of the framework extending around the corner thereof and lying flat against the adjacent side of framework, the sheet metal on said adjacent side extending up to the 95 corner of said framework and then being bent backwardly upon itself to contact with the sheet metal flattened against said frame- work.

VICTOR A. BENSON.
